UNITED STATES PATENT OFFICE.

ISAAC SAMUEL BUNNELL, OF EAST ORANGE, NEW JERSEY.

NEGATIVE-HOLDER.

1,259,355.

Specification of Letters Patent. Patented Mar. 12, 1918.

Application filed May 24, 1917. Serial No. 170,676.

To all whom it may concern:

Be it known that I, ISAAC SAMUEL BUNNELL, a citizen of the United States, and a resident of East Orange, in the county of Essex and State of New Jersey, have invented a new and Improved Negative-Holder, of which the following is a full, clear, and exact description.

The invention relates to the art of producing printing media as exemplified in the application for Letters Patent of the United States, Serial No. 56,297, filed by me on October 16, 1915. In the machine described in my application above referred to, use is made of a movable carriage supporting a sensitized film, a negative holder movable transversely and sidewise, and adapted to support a negative provided with fancy characters in spaced relation one to the other, and a source of light having a field capable of embracing at the time but a single one of the said fancy characters, the said carriage, the negative holder and the source of light having movement one relative to the other to allow making successive exposures of selected ones of the said fancy characters on the film and in assembled relation to the matter to be printed. In the machine described, the negative is firmly attached to the holder and separate negatives and holders are provided for each different set of fancy characters.

The object of the present invention is to provide a new and improved negative holder arranged to permit of holding negatives provided with alphabets of fancy capital and small letters or other fancy characters varying in height and to permit accurate positioning of a selected character for making an exposure on the sensitized film at the same time insuring accurate spacing between successive characters in the formation of words and sentences.

In order to accomplish the desired result, use is made of a base plate having means for removably supporting a negative, a gage plate slidable sidewise on the said base plate, the said plates having coacting positioning means, and a carrier slidable on the frame of the machine in a sidewise and transverse direction and having means adapted to be engaged by the said positioning means.

A practical embodiment of the invention is represented in the accompanying draw-

ings forming a part of this specification, in which similar characters of reference indicate corresponding parts in all the views.

Figure 1 is a cross section of the apparatus provided with the negative holder;

Fig. 2 is a plan view of the negative;

Fig. 3 is a plan view of the negative holder; and

Fig. 4 is a plan view of a portion of the holder with the parts in a different position.

On the top of the frame 12 of the machine is mounted to slide sidewise a carriage 13 provided with a depending box 14 and provided on its top with a front opening 17 and a rear opening 18, with a pad 19 of felt or other suitable cushioning means intermediate the said openings 17 and 18. Over the pad 19 passes a sensitized surface, preferably in the form of a sensitized film 20 (or photographic paper) which extends through the openings 17 and 18 into the box 14. The film 20 extends upward between the feed rollers 23 and 24 arranged within the opening 17, and the rear end of the film 20 passes between feed rollers 25 and 26 extending within the opening 18. The feed roller 25 is turned with a view to feed the film 20 rearwardly over the pad 19 whenever it is desired to do so by the operator during the act of printing.

In order to protect the sensitized film 20 against light, use is made of a protective opaque cover 40, of rubber or other suitable fabric material, and provided at its middle directly over the film portion overlying the pad 19 with an opening 41 for the passage of light from a source of light, preferably in the form of an electric lamp 93 contained in a casing 92 mounted on an arm 90 mounted to swing upward on the frame 12. The casing 92 is provided in its lower portion with a lens 94 for directing the rays of light from the lamp 93 through an opening 95 in the arm 90 and through a stop 96 onto and through the negative 50 to photographically print a corresponding letter of the alphabet on the film 20, which latter is at the time encompassed by the stop 96. The stop 96 is mounted in a suitable holder 97 removably held on the under side of the arm 90. The negative 50 of a transparent material extends over the opaque cover 40 and is provided with an alphabet of fancy capi-

tal letters 55 and an alphabet of fancy small letters 56, and each of the letters 55 of the alphabet has associated therewith but spaced therefrom a centering or positioning mark 57 preferably located directly above the exact middle of the corresponding letter, as shown in Fig. 2. A similar centering or positioning mark 58 is associated with each of the small letters 56. The negative 50 is attached at its front margin to a supporting plate 51 provided on the top with rows of capital and small letters 65, 66 with which are associated positioning marks 67 and 68, as plainly shown in Fig. 2. The capital letters 65 and their positioning marks 67 are in transverse alinement with the capital letters 55 and their positioning marks 57, and the small letters 66 and their positioning marks 68 are in transverse alinement with the corresponding small letters 56 and their positioning marks 58. A pointer 70 is attached to the front of the arm 90 and indicates on the letters 65 and 66 and their positioning marks 67 and 68.

5 In order to permit the use of a series of negatives 50 each having alphabets of fancy capital and small letters 55, 56 but with a variation in the height of said letters, use is made of a holder provided with a base plate 150 movable lengthwise and transversely on the top of the frame 12. The base plate 150 is provided with pins 151 adapted to be engaged by apertures 152 formed on the front margin of each plate 51 to hold the latter and its negative 50 removably in position on the base plate 150. A gage plate 153 overlies the base plate 150 and the negative 50 and its supporting plate 51 extend over the gage plate 153 and the latter is adapted to be shifted a short distance on the base plate 150 in a sidewise direction. For this purpose use is made of screws or pins 154 attached to the base plate 150 and extending through longitudinal slots 155 formed in the gage plate 153. Handles 156 are mounted on the gage plate 153 and are adapted to be taken hold of by the operator to permit the latter to shift the gage plate from the right to the left or vice versa. The base plate 150 is also provided at its front corners with handles 157 to permit of conveniently placing the holder in position on the frame 12 or removing it therefrom whenever it is desired to do so.

10 The base plate 150 is provided with a central member 160 and end members 161 and 162 spaced from the central member 160 at opposite sides thereof. On the base plate 150 and extending between the members 160 and 161 is formed a plurality of transverse arms 163 arranged in step form and forming between them transverse slots 164. Similar arms 165 are formed on the base plate 150 between the central member 160 and the end member 162, and these arms 165 form slots 166 be-

15 tween them. Corresponding pairs of slots 164 and 166 on opposite sides of the central member 160 are adapted to be engaged with pins 170 and 171 rising from a bar 172 extending within a recess 173 formed in the top of the frame 12, as plainly shown in Figs. 1 and 3. The recess 173 is sufficiently large to permit the bar 172 to slide sidewise therein and also in a transverse direction. The front and rear wall of the recess 173 are provided with plates 174 and 175 provided at their opposite edges with teeth 176 and 177 adapted to be engaged by corresponding teeth 178 and 179 formed on the front and rear edges of the bar 172.

20 In order to lock the pins 170 and 171 of the bar 172 in position in corresponding pairs of slots 164, 166 to cause the bar 172 to move with the base plate 150 when the latter is shifted in a sidewise direction and to allow of moving the bar 172 in a transverse direction with the base plate 150, the following arrangement is made: The gage plate 153 is provided with arms 180 and 181 spaced apart to form slots 182 adapted to register with the corresponding slots 164, 166 or to move out of register with the same as will be readily understood by reference to Figs. 3 and 4. Each of the arms 180 and 181 is provided with cut-out portions 184 to vary in length according to the height of the letters 55, 56 and the spaces between the same on the negative 50. It will be noticed that by the arrangement described the base plate 150 and the gage plate 153 can be moved in engagement at any pairs of slots 164, 182 and 166, 183 with the pins 170, 171, after which the gage plate 153 is shifted to the right to locate the pins 170, 171 at the corresponding notches 184 or the ends of the corresponding arms 180, 181. It is understood that the aggregate movement of the bar 172 transversely in the recess 173 and the length of the corresponding slot 184 correspond to the height of the letter 55 or 56 used at the time. When the negative 50 is in position on the holder and the latter is engaged with the pins 170, 171, as above mentioned, then the holder device can be moved transversely and sidewise to move the corresponding letter in position under the stop 96. In practice the arms 180 and 181 are provided with numerals (see Fig. 3) indicating the height of the letters 55, 56 of the several negatives 50 thus enabling the user to quickly engage the pins 170, 171 with the corresponding slots 164, 182 and 166, 183, according to the height of the letters 55, 56 of the negative 50 used at the time. It is understood that the letters 55 and 56 are spaced apart a distance corresponding to that of the transverse movement of the holder so that either set of letters 55 or 56 can be moved in register with the opening 41 on shifting the base plate 180

150 rearwardly or forwardly according to whatever capital or small letter is required at the time for reproduction on the film 20.

Having thus described my invention, I 5 claim as new and desire to secure by Letters Patent:—

1. In a device for producing printing media, a negative holder, comprising a base plate having means for removably supporting a negative, a gage plate slidable sideways on the said base plate, the said plates having a coacting positioning means, and a bar determining the height of a character used at the time and slidable on the frame 10 of the machine in a sidewise and transverse direction the bar having means adapted to be engaged by the said positioning means.

2. In a device for producing printing media, a negative holder, comprising a base plate having means for removably supporting a negative, a gage plate slidable sideways on the said base plate, the said plates having spaced arms arranged in step form 15

and adapted to form slots between them, the arms of the gage plate having notches of varying length, and a bar determining the height of a character used at the time and slidable lengthwise and transversely on the frame of the machine the said bar having pins adapted to engage corresponding slots. 25

3. In a device for producing printing media, a negative holder, comprising a base plate having means for removably supporting a negative, a gage plate slidable sideways on the said base plate, the said plates 30 having a coacting positioning means, a bar determining the height of a character used at the time and slidable on the frame of the machine in a sidewise and transverse direction the bar having means adapted to be 35 engaged by the said positioning means, and coacting means on the base plate and bar for guiding the bar into accurate and final position and holding it there. 40

ISAAC SAMUEL BUNNELL.
